UNITED STATES PATENT OFFICE.

IGNATIUS SINGER AND MORITZ W. JUDELL, OF LONDON, ENGLAND.

APPARATUS FOR CLEANSING WOOL.

SPECIFICATION forming part of Letters Patent No. 415,314, dated November 19, 1889.

Application filed January 14, 1889. Serial No. 296,277. (No model.) Patented in South Australia January 16, 1888, No. 945, and January 17, 1889, No. 1,212; in Victoria January 17, 1888, No. 5,566, and January 14, 1889, No. 6,457; in New South Wales January 18, 1888, No. 443, and January 17, 1889, No. 1,185; in Queensland January 20, 1888, No. 387, and January 16, 1889, No. 688; in New Zealand January 30, 1888, No. 2,772, and January 29, 1889, No. 3,511; in Tasmania January 31, 1889; in England February 20, 1888, No. 2,532, and October 3, 1888, No. 14,247; in Belgium March 3, 1888, No. 80,861; in Luxembourg March 6, 1888, No. 964; in Germany March 23, 1888, No. 46,015; in Canada April 26, 1888, No. 29,010; in Cape of Good Hope May 25, 1888, No. 6/307; in India May 29 and June 20, 1889, Nos. 106 and 107; in Spain June 30, 1888, No. 7,998; in Italy July 12, 1888, XLVI, 301; in Austria-Hungary October 3, 1888, No. 18,530 and No. 31,644, and in France March 9, 1888, No. 189,234.

To all whom it may concern:

Be it known that we, IGNATIUS SINGER and MORITZ WOLFF JUDELL, subjects of the Queen of Great Britain, both residing at 5 Gresham House, Old Broad Street, in the city of London, England, have invented a new and useful Improved Apparatus for Cleansing Wool and like Material, (for which we have received patents in Great Britain October 3, 10 1888, No. 14,247; in France, by patent of addition dated December 8, 1888, No. 189,234; in Victoria January 14, 1889, No. 6,457; in New South Wales January 17, 1889, No. 1,185; in New Zealand January 29, 1889, No. 3,511; 15 in South Australia January 17, 1889, No. 1,212; in Queensland January 16 and July 5, 1889, No. 688; in India May 29 and June 20, 1889, No. 106; also partly patented in Austria-Hungary October 3, 1888, Nos. 18,530 and 20 31,644; in Belgium March 3, 1888, No. 80,861; in Canada April 26, 1888, No. 29,010; in Cape of Good Hope May 25, 1888, No. 6/307; in France March 9, 1888, No. 189,234; in Germany March 23, 1888, No. 46,015; in Great 25 Britain February 20, 1888, No. 2,532; in India May 29 and June 20, 1889, No. 107; in Italy July 12, 1888, Vol. 46, No. 301; in Luxembourg March 6, 1888, No. 964; in New South Wales January 18, 1888, No. 443; in New Zealand 30 January 30, 1888, No. 2,772; in Queensland January 20 and April 28, 1888, No. 387; in South Australia January 16, 1888, No. 945; in Spain June 30, 1888, No. 7,998; in Tasmania January 31, 1888, and in Victoria January 17, 35 1888, No. 5,566,) of which the following is a specification.

Our invention relates to apparatus for cleansing wool from the oily and fatty matters, the saline matters, and the mechanical 40 impurities which are generally associated with it, our object being to deliver the wool in a clean dry state ready for manufacture, separating from it the impurities in such form that the oil and fatty matters can be obtained 45 as useful products, and the bisulphide of car-

bon which we use as the solvent can be recovered for subsequent use. We will describe the apparatus which we employ for this purpose, referring to the accompanying drawings.

Figure 1 is a longitudinal section of the 50 macerator and drying-chamber connected therewith. Fig. 1^a is a detail sectional view illustrating means for steam-heating certain of the rolls. Fig. 1^b is a sectional view illustrating a modified construction of the partitions which divide the macerator into separate cells. Fig. 2 is a transverse section of the macerator at *x x*, Fig. 1; and Fig. 3 is a side elevation of part of the macerator, a portion of the casing being broken away to show 60 the interior at *x x*.

The macerator A is a long vessel divided into a number of cells by vertical double partitions. At the one end B several of the cells are deeper than the others, and their double 65 partitions are made as shown at C, that on the right reaching higher than that on the left, but not reaching quite to the bottom of the cells. The other cells D have also double partitions E, the left being the higher, but not 70 reaching quite to the bottom. The partitions become lower and lower toward the left end of the macerator. In several of the cells F, at the left hand, are arranged dredgers, which will be more particularly described herein- 75 after, and, finally, at the extreme left there is a deposit-cell G, containing a filter g, above which is an outflow-pipe g', and below which is a pipe and cock g², which can be opened for emptying the cell.

On the extreme right of the macerator is a feed-cell H, which is supplied by a pipe h with water and bisulphide of carbon. In this cell is a float h', adjusted so that it will float on the heavier liquid bisulphide of carbon 85 and sink in water, so that it takes a position at the level where the two liquids meet in obedience to their relative gravities. The vertical float-rod is linked to the long arms of two levers h² h³, the short arms of which 90

carry valves governing the mouths of two pipes h^4 and h^5 . When, owing to excess of bisulphide of carbon, the float h' rises, it closes the valve of pipe h^4 and opens that of pipe h^5 , 5 allowing a portion of the bisulphide to flow to the first of the cells B. When, on the other hand, float h' sinks, it closes the valve of pipe h^5 and opens that of pipe h^4 , admitting water to the first of the cells B. The water over- 10 flows from cell to cell, finally escaping from the last by a pipe b. In like manner the bisulphide admitted by the pipe h^5 overflows from cell to cell of the ranges D and F, finally 15 into the deposit-cell G, and, depositing there solid matters suspended in it, passes through the removable filter g and away by the pipe g' .

There are two continuous traveling aprons K and L, of wire-gauze or other porous fabric, which pass over guide-rollers and travel 20 together in the direction of the arrow between a number of pairs of pressing-rollers k and under idlers l, one set for each cell, then ascend a shaft M to the drying-chamber N, in which they are similarly conducted be- 25 tween a number of pairs of pressing-rollers k' and under idlers l', the pressing-rollers in this case being steam-heated—as, for instance, as shown in Fig. 1^a, where one of the rolls K' is shown in section provided with suitable 30 stuffing-boxes and ingress and egress steam-pipes k^5 k^6 . Beyond the left end of the drying-chamber N, after passing between the pressing-rollers k², the two aprons K L separate, to come together again at the first pair 35 of the pressing-rollers k. Fleeces of wool, being laid on the lower apron at K', are carried by the two aprons continuously through the successive cells of the macerator F, D, and B, then back through the drying-chamber N, 40 and are discharged onto an inclined chute L'. The wool in thus traveling through the macerator from left to right, while the bisulphide of carbon travels from right to left, meets purer and purer bisulphide as it advances to- 45 ward B, while the bisulphide meets wool more and more greasy as it flows toward G. In its passage along the macerator the wool is repeatedly immersed in the solvent, which is mostly pressed out by the rollers k after each 50 immersion. After leaving the last of the cells D it passes in like manner through the water-cells B, in which such salts as it contains that are soluble in water are washed out. The wool then passes up the shaft M and along 55 the drying-chamber N, subject to the action of the heated rollers, and finally is delivered on the chute L' in a clean dry condition, ready for manufacturing purposes.

Such being the general character and operation of the apparatus, there are certain details, which we now proceed to explain.

The shaft M and the drying-chamber N communicate with a cooling-worm O, by which the vapors are condensed, the water and the 65 bisulphide which result from the condensation being conducted by the pipe o to supply again the macerator-cells. In order to pro-

mote passage of the vapors to the condenser, a steam-jet may be applied at n to act as an injector. The macerator A B is entirely cov- 70 ered in, and partitions at f' and b' extend down into water, which acts as a seal to prevent escape of vapor evolved from the cells, such vapor passing by an opening at a, governed by a valve, into the shaft M, and thence 75 to the condenser.

In order to get access to different parts of the macerator and drying-chamber, there are a number of openings through their covers, each closed by a flanged cap a', the flange of 80 which projects down into water, forming a seal against escape of vapor.

In several of the macerator-cells, as indicated at F, there are provided dredgers, as shown to an enlarged scale in Figs. 2 and 3, 85 each consisting of a chain of buckets P, which pass round along the bottom of the cell, scrape up such solid matters as are deposited there in the form of sludge, and deliver it into a trough-receiver, from which it is conveyed 90 by a worm p to an inclined chute p', Fig. 1, leading out at the side of the macerator. For working the pressing-rollers k we provide a revolving shaft Q, extending along the side of the macerator within a casing q. This shaft 95 by bevel-gear, or, it might be, by worm-gear, works the lower one of each pair of pressing-rollers k, the upper one, as well as the idler l, being left free to be rotated by the travel of the aprons K and L. A similar arrangement 100 of driving-gear is applied to the rollers in the drying-chamber N. The fluid that issues at g', being a solution of fatty matter in bisulphide of carbon, is dealt with by distillation, 105 evaporating the solvent, which is condensed for subsequent use, and leaving comparatively-pure fatty matter in the still.

The sludge dredged up from the cells F and delivered from the chute p', as well as that removed from time to time from the deposit-tank G, is also subjected to distillation for recovery of solvent. As these are known processes, we do not describe apparatus for effecting them, there being several known forms of apparatus for that purpose.

For the purpose of emptying the macerator, each cell of it may communicate with the next by a small passage close to the bottom, each of these passages being provided with a valve, which can be opened, so as to form a 120 continuous passage along the bottom of the macerator to the pipe and cock g². Such a passage e and valve e' are shown in Fig. 1^b, said valve being adapted to be moved up or down to open or close the passage by means 125 of a handled rod e²; or a general drain-pipe (indicated by the dotted lines g³ and g⁴, Fig. 1) may communicate with the bottom of each cell by a branch provided with a cock or valve, which can be opened to empty the cell 130 when desired.

Having thus described the nature of our invention and the best means we know of carrying it out in practice, we claim—

1. In a wool-cleansing apparatus, the combination of a macerator consisting of a series of cells arranged in two sets adapted to contain, respectively, a solvent of oil and water, as described, the cells of each set communicating with each other in succession by suitable overflow-openings, a deposit-cell or collecting-chamber for the grease at the end of the series, provided with a filtering or straining device, and an open or porous conveyer passing into and out of said cells of both sets, substantially as set forth.
2. In a wool-cleansing apparatus, the combination of a macerator consisting of a series of cells arranged in two sets adapted to contain, respectively, a solvent of oil and water, as described, the cells of each set communicating with each other in succession by suitable overflow-openings, the said openings of one set leading from the top of one cell to the bottom of the next, and an open or porous conveyer passing into and out of said cells of both sets, substantially as set forth.
3. In a wool-cleaning apparatus, the combination of a macerator having a series of water-cells communicating the top of one cell with the bottom of the next succeeding, a series of cells for the solvent communicating the bottom of one cell with the top of the next succeeding, and an open or porous conveyer passing into and out of said cells of the series, substantially as set forth.
4. The combination, with the macerator having a series of cells and the feed apparatus for supplying a solvent thereto, of a drying-chamber, an open or porous conveyer passing through said cells and through the drying-chamber, a condenser communicating with the drying-chamber and adapted to receive the vapors of said solvent therefrom, and a conduit from said condenser to said feed apparatus for returning the condensed solvent thereto, substantially as set forth.
5. The combination, in a macerator, with a series of cells and an open or porous conveyer passing along said series and into and out of the several cells, of dredgers mounted on shafts above said conveyer, passing around the same and through the cells beneath the conveyer, substantially as set forth.
6. In a macerator, the combination, with a series of cells and a conveyer passing from one cell to the other over their dividing-partitions, of the closed chamber A, covering the portions of said conveyer above the cells, a series of openings into said chamber for giving access to the cells, the water-sealed covers for said openings, and the end partitions of said chamber passing into the end cells at points where the conveyer passes below their liquid contents, substantially as set forth.
7. The combination, with the series of cells communicating one with the other in succession, of the conveyer passing from one cell to the next over their intervening partitions, the final deposit-chamber G, the exit-pipe g' , and the filter g below said pipe and above the chamber, substantially as set forth.
8. The combination, with a series of cells of gradually-decreasing height and adapted to conduct through said cells a stream of solvent from the higher to the lower end of the series, of a porous or open conveyer passing into and out of said cells over their intervening partitions and from the lower toward the higher end of the series, substantially as set forth.
9. The combination, with a tank adapted to contain liquids of different gravities and provided with an exit-pipe from its upper part and a second exit-pipe from its lower part, of valves in said pipes, mechanism connecting and adapted to operate said valves, and a float attached to said mechanism and situated below the one and above the other of said exit-pipes, substantially as set forth.
- In testimony whereof we have signed our names to this specification, in the presence of two subscribing witnesses, this 3d day of December, A. D. 1888.
